US0D1081259S

(12) **United States Design Patent** (10) Patent No.: **US D1,081,259 S**
(45) Date of Patent: ** Jul. 1, 2025

(54) **PASTRY BEATER**

- (71) Applicant: **WHIRLPOOL CORPORATION**,
Benton Harbor, MI (US)
- (72) Inventors: **Naveen Jayabalan**, Stevensville, MI
(US); **Brandon T. Mock**, St. Joseph,
MI (US); **Joseph Snyder**, Benton
Harbor, MI (US); **Jeremy T. Wolters**,
Stevensville, MI (US)
- (73) Assignee: **Whirlpool Corporation**, Benton
Harbor, MI (US)

(**) Term: **15 Years**

(21) Appl. No.: **29/926,704**

(22) Filed: **Jan. 31, 2024**

Related U.S. Application Data
